BRAKE SHOE MOUNTING

Robert B. Pogue, Chicago, Ill., assignor to The American Brake Shoe and Foundry Company, Wilmington, Del., a corporation of Delaware

Application October 18, 1930. Serial No. 489,621

6 Claims. (Cl. 188—243)

This invention relates to brake shoes for railway cars and more particularly to a novel manner and means for mounting the shoe in place for service.

It is customary to removably secure a shoe in a supporting head by means of a fastening key, considerable clearance being allowed between the interengaging parts of the shoe and head to enable the shoe to be easily set in place and secured by the key. The shoe is provided with lugs on its back which engage parts on the head, and it is found that excessive wear of these engaging parts results from the constant vibration of the shoe and head in service. As the wear of the parts continues the fit becomes looser, the vibrations become greater, and the wearing effect correspondingly increases in intensity. It is also known that the varying degrees of heat to which a shoe is subjected in service soon produces heat checks in the wearing face of the shoe which progress in depth and become substantial fractures in the body of the shoe. This progression of the heat checks to fracture is greatly accelerated by the vibration to which the shoe is subjected in service and results in parts of the body falling away or in the reenforce back bending and finally breaking. This vibration effect upon the body and back of the shoe increases as the interengaging parts of the shoe and the head wear to looser fit, and this has been found to occur generally during the early period of service of the shoe. When the body of the shoe fractures, the vibrations of service cause small parts of the body at the fracture to work loose and fall away, and this loosens the body on the reenforcing back and increases the vibration effect which is further increased by looseness of fit of the shoe on the head due to wear. After the shoe fractures service vibrations are communicated directly to the reenforcing back of the shoe at or about the point of fracture, and these vibrations are increased in intensity as the fit of the shoe on the head wears and because the head fails to provide a proper support for the shoe.

The primary object of my invention is to overcome the difficulties hereinbefore mentioned, and others incident thereto, by providing a simple and novel means for removably securing and supporting a brake shoe in a brake head in substantially rigid position for service so that it will be protected against the ill effects of wear on the head.

Another object is to employ a spring steel fastening key and to provide for and require that

this key be deflected in securing the shoe to the head so that the shoe will be held in substantially rigid position on the head and practically free from vibration relative to the head.

And a further object of the invention is to provide a brake head of novel construction which will form a substantial back support for the shoe and cooperate with the fastening means in holding the shoe in substantially rigid position to avoid weaving or bending or other relative movement of parts at or adjacent the fracture in the shoe.

In the accompanying drawing I have illustrated a selected embodiment of the invention with a common cast iron car shoe having a steel strip lug of similar form, and referring thereto

Fig. 1 is a sectional view on the line 1—1 of Fig. 3;

Fig. 2 is a sectional view on the line 2—2 of Fig. 1;

Fig. 3 is a sectional view on the line 3—3 of Fig. 1; and

Fig. 4 is a perspective view of the fastening key.

Referring to the drawing, the brake head comprises two side members 5, 5 which are connected together at the back by the socket member 6 having an opening 7 to receive the brake beam. These sides are also provided at the top with aligned openings 8 to receive a hanger. At the front of the head the sides are connected by a face plate 9 which is divided into two parts by the centrally disposed recess 10 to receive the attaching lug 11 of the brake shoe 12. The recess extends through the sides of the head and it is preferably of a size adapted to receive the attaching lug snugly. The ends of the head engage the end lugs 13 on the shoe, and the face plate of the head is recessed at 14 to receive the guide lugs 15 on the shoe to hold the shoe aligned with the head. On the back of the face plate at the top and bottom of the recess 10 there are bearing lugs 16 which have inclined back faces 17 disposed in relation to the recess 10 and the opening 18 in the attaching lug of the shoe to form guides for the fastening key 19 and to hold this key in deflection while it secures the shoe in the head. The lugs project rearwardly from the face plate of the head to align substantially with the top wall of the opening in the attaching lug of the shoe and sufficiently to hold the key so tightly in deflection that it will not work loose or permit movement of the shoe in the head. The inner end of the

105
110

inclined face 17 of the lower lug 16 is so located that when the key is inserted in the attaching lug at the top thereof (Fig. 1) and bearing against the outer end of the inclined face of the upper lug 16 the lower end of the key will engage the inclined face of the lower lug 16 and slide thereon, under pressure or blows supplied to the head of the lug, to deflected locking position as shown in Fig. 1. For convenience in manufacture, and especially on a reversible head, both of the lugs 16 are preferably made uniform in shape, as shown. When the key is in operative position securing the shoe in the head it will be deflected considerably and will hold the shoe substantially rigid in the head and free from relative vibration between the shoe and the head. It will not be difficult to insert the key because its lower end will be guided to the inclined face of the lower lug by the high point of the upper lug and the attaching lug of the shoe, and after the end of the key engages the inclined face of the lower lug it can be forced to locking position, as shown, by pressure or blows on its head.

While the invention is not expected to prevent heat checks in the wearing face of the shoe due to the varying temperatures to which the shoe is subjected in service, it will to a very large extent, if not fully, prevent the checks from progressing to open fractures and this, in turn, will prevent the weaving action which has been incident to fractured shoes, and bending and breaking of the reenforce backs. The face plate of the head forms a substantially full coverage support for the back of the shoe except at the lugs thereon, and assists in holding the shoe in substantially rigid position and free from substantial vibration relative to the head.

This invention does not require any change in standard forms of shoes, and the shoes in the heads simplify the construction of the head and do not add to the weight or to the difficulties of casting.

I have shown the invention in a selected freight car shoe and head of simple construction to explain the invention and its advantages, but I do not mean thereby to restrict the invention to the form and construction shown. I may embody the invention in other forms of freight car shoes and heads, and in passenger car and locomotive shoes and heads, and in flanged and unflanged shoes, and I reserve the right to make any changes in the form, construction and arrangement of parts as may be necessary or desirable within the scope of the following claims:

I claim:

1. The combination of a brake shoe having an attaching lug, a brake head having a recess to receive the attaching lug and bearing lugs

above and below the recess and adjacent thereto, and a fastening key passing through the attaching lug and engaging the bearing lugs, said lugs holding the key in forward deflection between the bearing lugs and with its end portions extending rearwardly above and below the bearing lugs.

2. The combination of a brake shoe having an attaching lug, a brake head having a recess to receive the attaching lug and bearing lugs above and below the recess and adjacent thereto, said bearing lugs extending to align substantially with the top wall of the opening in the attaching lug, and a fastening key passing through the attaching lug and engaging the bearing lugs and being held in forward deflection by said lugs to secure the shoe on the head.

3. The combination of a brake shoe having an attaching lug, a brake head having a recess to receive the attaching lug and bearing lugs above and below the recess and adjacent thereto, and a flat resilient fastening key passing through the attaching lug and engaging the bearing lugs, said lugs holding the key in forward deflection between the bearing lugs and with its end portions extending rearwardly above and below the bearing lugs.

4. The combination of a brake shoe having an attaching lug, a brake head having a recess to receive the attaching lug, and a fastening key engaging the attaching lug and securing the shoe on the head, said head having bearing lugs thereon above and below the recess to hold the key in deflection while in engagement with the attaching lug and prevent movement of the shoe on the head, said bearing lugs having back faces inclined forwardly and toward each other.

5. The combination of a brake shoe having an attaching lug, a brake head having a recess to receive the attaching lug, and a fastening key engaging the attaching lug and securing the shoe on the head, said head having bearing lugs thereon above and below the recess to hold the key in deflection, the back face of the upper bearing lug being inclined downwardly and forwardly to permit insertion of the key in the attaching lug, and the back face of the lower bearing lug being inclined upwardly and forwardly to receive the end of the key as it projects through the attaching lug and to cause the key to deflect as it is driven to final position.

6. A brake head having a face plate and a recess therein to accommodate the attaching lug of a brake shoe, and bearing lugs on the back of the face plate above and below said recess, said bearing lugs having back faces inclined forwardly and toward each other.

ROBERT B. POGUE.
